GOVERNOR

George Forrest Drake, Rockford, Ill., assignor to
 Woodward Governor Company, Rockford, Ill.,
 a corporation of Illinois

Application February 27, 1942, Serial No. 432,579

11 Claims. (Cl. 264—4)

This invention relates to governors for regulating the speed of prime movers and more particularly to those adapted for isochronous operation.

One object is to provide a governor of the above character having a compensating mechanism of novel and compact construction and capable of producing improved stability and accuracy of speed control.

Another object is to provide an hydraulic isochronous governor in which the mechanism for modifying the governor action to obtain temporary speed droop is carried by and movable with the movable element of the servo actuator.

A further object is to arrange the receiving piston of an hydraulic compensating mechanism within the servo piston.

Still another object is to provide a novel arrangement of springs for modifying the governor action and for restoring normal speed of the prime mover.

Other objects and advantages of the invention will become apparent from the following detailed description taken in connection with the accompanying drawings, in which.

Figure 1 is a vertical central sectional view of a governor constructed in accordance with the present invention.

Figs. 2, 3, 4, and 5 are sections taken respectively along the lines 2—2, 3—3, 4—4, and 5—5 of Fig. 1.

While the invention is susceptible of various modifications and alternative constructions, I have shown in the drawings and will herein describe in detail the preferred embodiment. It is to be understood, however, that I do not intend to limit the invention by such disclosure but aim to cover all modifications and alternative constructions falling within the spirit and scope of the invention as expressed in the appended claims.

In the governor shown for purposes of illustration all of the operating parts are housed in a casing 6 usually mounted on the prime mover to be controlled and having a tubular extension 7 at its upper open end which is closed by a cover 8. Changes in the prime mover speed are detected by upstanding weights or flyballs 9 pivoted on horizontal pins 10 on a head 11 which rests on a ledge 12 of the casing. The head is integral with the upper end of a sleeve 13 journaled in a vertical bore 14 with its lower splined end 15 projecting from the casing bottom for connection with a suitable drive shaft driven by the engine.

Arms 16 on the flyballs bear upwardly against the lower race ring 17 of a thrust bearing having balls 18 supporting an upper ring 19 which abuts against a shoulder 20 on a rod 21 reciprocable in a bore 22 of the sleeve 13 and carries an enlarged head or piston 23 at its lower end cooperating with sleeve ports 24 which have a diameter substantially the same as the length of the piston. The valve thus formed controls the flow of pressure fluid or oil through a groove 25 around the sleeve and a passage 26 leading to the lower end of a vertical cylinder 27 on the side of the casing opposite the valve structure. A piston 28 reciprocates in this cylinder and cooperates therewith to form a servomotor for variably positioning a throttle rod 29 or other device by which the speed of the engine is regulated. Herein the upper end 30 of the servo piston bears against curved surfaces 31 on the bifurcated end of a crank 32 fast on a horizontal rockshaft 33 which is journaled intermediate its ends in a plug 34 which threads through one side of the casing 6. The shaft may be connected to the throttle rod through a crank 35 on the outer shaft end, a spring 29a which acts on the rod providing the loading necessary to balance the hydraulic forces.

Pressure fluid is supplied by a pump 36 preferably comprising gears 37 and 38 disposed in a recess 39 in a plate 40 clamped against the casing bottom, the gear 37 being splined on the drive sleeve 13. Oil supplied under pressure by the pump is delivered through a passage 41 to a horizontal passage 42 surrounding an external groove 43 formed in the sleeve 13 above the groove 25. The pump inlet is adapted to communicate with an oil supply line 44 through a hole 45 in a sleeve 46 connected at its outer end to the line 44 with its inner end projecting into the passage 42. When an excessive supply of pressure develops, a piston 47 in the sleeve is shifted against a spring 48 to uncover a port 49 and permit the by-pass of oil to the pump inlet. In this way, the oil in the passage 42 is maintained at constant pressure.

The tendency of the flyballs to lift the pilot valve rod is counteracted by a main speeder spring 50 of frusto-conical shape acting between a washer 53 on the upper end of the valve rod 21 and a cross-head 54 guided in vertical ways 55 on the casing sidewalls. Adjustment of the speeder spring stress is effected herein by turning knurled head 56 of a screw 57 threading into a boss on the casing and bearing at its inner end against a lug 58 on a crank 59. The latter

is pivoted on a stud 60 and its bifurcated end 61 bears down against the top of the cross-head. The speed setting is increased when the crank is swung downwardly by the screw.

The present invention contemplates the provision of mechanism self-contained within the servo element 28 and responsive to the movement thereof to derive the forces necessary to impart a temporary speed droop characteristic to the governor. Herein, this mechanism operates hydraulically and includes a compensating receiving piston 62 slidable in a cylinder 63 formed by constructing the servo piston as a hollow sleeve. The transmitting or actuating piston comprises a plug 64 closing the lower end of the servo piston sleeve 28. The plunger 62 has a hollow stem 65 with an enlargement 66 guided in the cylinder 63 and fluted longitudinally as indicated at 67 to permit of the free flow of oil upwardly from the chamber 68 between the enlargement and the plunger 62. Small clearance is provided between an inturned flange 69 on the upper end of the sleeve 28 and the portion of the piston rod which projects from the sleeve. By fitting the servo piston or sleeve 28 loosely into the cylinder 27, oil from the pressure chamber 26 leaks upwardly along the piston and flows through holes 70 in the sleeve to keep the chamber 68 filled at all times.

The plunger 62 cooperates with the cylinder 63 and the plug 64 to define a chamber 71 which is closed except for leakage through an axial bore 76 in the stem 65 as permitted by a needle valve 72 to control the compensation or restoring action. Preferably, though not necessarily, the valve is incorporated in the enlarged upper end of plunger stem 65 in a manner to permit leakage to and from the chamber 71 through the constantly filled chamber 68 and at the same time be accessible for convenient adjustment. To this end, the valve comprises a needle 73 projecting into an orifice 74 at the end of a passageway 75 drilled in the enlargement 66 and communicating with the chamber 68. At its upper end, the passage joins the passage 76 extending axially through the stem 65 and communicating with the chamber 71. The needle is on a screw 77 that threads into a bore in the enlarged projecting portion of the stem at such an angle that the screw head is accessible for adjustment from a point exteriorly of the servo piston 28.

A novel means is provided for transmitting to the governor pilot valve the forces derived by motion of the piston 62 so as to produce speed droop and then compensate therefor so as to render the droop only temporary. This means includes an auxiliary spring 77 acting in parallel with the main speeder spring 50 to either increase or decrease the loading of the flyballs according to the direction and extent of movement of the compensating receiving piston 62 away from the neutral or equilibrium position shown in Fig. 1. Herein the auxiliary spring comprises a coil acting either in tension or compression on the upper end of a rod 78 projecting up through the cross-head 54 and the main spring with its lower end pinned to the upper end of the pilot valve stem 21. One end of the coil is fastened to the rod 78 while the other end is secured to a block 79 pivotally connected at 80 to a horizontal lever 81 fulcrumed on a pin 82 disposed adjacent to the spring. The opposite end of the lever is connected by a pivot pin 83 to the upper end of the stem 65 of the receiving piston 62. To permit the lever ratio to be adjusted as desired, the pin 82 is disposed in a slot 84 in the lever and is

supported on a block 85 clamped by a bolt 86 to a bracket 87 on the casing section 1 (see Figs. 3 and 4). The bolt projects through a slot 88 in the bracket paralleling the lever so that the block 5 may be set at different positions along the slot to vary the spacing of the pivots 80 and 82 and therefore the ratio of motion transmission from the piston 62 to the spring 77.

To provide for effective return of the lever 81 to its neutral position while permitting the auxiliary spring 77 to exert an effect which is small as compared to the main spring 50, a second spring 89 is arranged to act on the lever 81 at a point adjacent the stem 65. This spring is substantially stronger than the spring 77 and also acts in tension or compression, having one end fastened to a block 90 pivoted at 91 on the lever and its lower end attached to a cross-bar 92 which is fastened to integral ledges 93 on the 20 casing.

Operation

When the governor has attained equilibrium, 25 the parts will be positioned as shown in Fig. 1, the chamber 68 being filled with oil by leakage up past the servo piston and through the holes 70. There will be no pressure in the chambers 68 and 71, and the springs 77 and 89 exert no force on the lever 81, the speed setting of the governor being then determined solely by the spring 50.

First assume that the load on the engine increases resulting in a decrease in speed. In response to this the flyballs 9 move in dropping the 35 pilot valve piston 23 below the ports 24 so as to admit pressure fluid to the chamber 26. This raises the servo piston 28 and through the crank 32 rocks the shaft 33 to shift the rod 29 and increase the throttle opening. At the same time, 40 the receiving plunger 62 is raised with the servo piston because the valve 72 blocks the rapid escape of fluid from the chamber through the passages 76 and 78. The lever 81 is thus raised away from its neutral position and the springs 77 and 45 89 extended correspondingly. The spring 77, being now under tension, counteracts the effect of the spring 50 and in effect reduces the speed setting of the governor so as to permit recentering of the pilot valve plunger 23 relative to the ports 50 24 at a lower engine speed thereby producing speed droop and preventing hunting. When the 55 valve becomes recentered and the servo piston 28 is brought to rest, the plunger 62 will be urged downwardly by the combined tensile forces of the two springs 77 and 89, the oil in the chamber 71 thus being placed under pressure. This oil is permitted to leak out into the chamber 68 through the passage 76, the needle valve 72 and the passage 75 so that the plunger 62 and the 60 lever 81 are permitted to move downward gradually. As an incident to this, the speed setting of the governor is increased progressively so that the servo piston 28 moves to increase the throttle setting still further. This compensating action 65 continues until the original speed setting of the governor has been restored which occurs when, by leakage of oil through the valve 72, the lever 81 and the plunger 62 have been restored to their neutral position with the servo piston and the 70 throttle in their new positions which correspond to the increased load. The result of this compensating action is that the speed droop initially produced in response to the speed change in order to secure stability of engine operation is dissipated gradually and the initial speed setting of 75

the governor is restored regardless of the servo position and therefore the load on the engine.

In response to overspeeding of the engine, the action above described is reversed. That is, the pilot valve plunger 23 is raised permitting fluid in the chamber 26 to escape through the drain passage 95 with a consequent lowering of the servo piston and a decrease in throttle opening. As an incident to this, the plunger 62 follows because the needle valve restricts the fluid flow from the chamber 68 to the chamber 71. Thus, the springs 77 and 89 are compressed and the governor speed setting increased correspondingly. Under the influence of spring effects, the plunger 62 is raised relative to the servo piston as permitted by the flow of oil through the valve 72 into the chamber 71 with the result that the throttle opening is gradually reduced until equilibrium is again restored under the new load condition. The needle valve is of course adjusted to permit the springs to recenter the pilot valve in exact unison with the return of the engine speed to normal.

It will be observed that by adjusting the position of the lever fulcrum 82, the magnitude of the temporary speed droop and therefore the stability of the governor may be changed as desired. Also, the action of the auxiliary spring 77 is not in any way influenced by the supplemental return spring 89 which latter spring may therefore be as strong as may be required in order to effect proper recentering of the lever.

By arranging the compensating receiving plunger within the servo piston and transmitting the droop and restoring motions to the pilot valve as above described, extreme compactness is obtained, and the construction as a whole is greatly simplified as compared to that of prior isochronous governors. Thus, the addition of the compensating feature does not complicate the construction of the main pilot valve nor necessitate the use of a special connection for driving the flyballs. Moreover, by applying both the speed droop and compensating connections to the upper end of the pilot valve stem and in parallel with the main speeder spring, all of the adjustments are made conveniently accessible.

I claim as my invention:

1. A governor having, in combination, rotatably mounted, spring loaded flyballs, a servo actuator including a stationary cylinder and a piston reciprocable therein, a pilot valve actuated by said flyballs and operable selectively to admit pressure fluid to said cylinder or permit the escape of fluid therefrom, a second fluid filled cylinder closed at one end and disposed within said piston so as to move therewith, a plunger reciprocable in said second cylinder, a valve on said plunger controlling the flow of fluid into and out of the chamber between said plunger and the closed end of said second cylinder, a lever swingable in opposite directions from a neutral position, an auxiliary spring actuated by said lever to increase or decrease the loading on said flyballs according to the direction of lever movement relative to said neutral position, means connecting said lever to said plunger, and a second spring acting between said lever and a fixed point and urging the lever toward said neutral position.

2. A governor having, in combination, rotatable spring loaded flyballs, a servo actuator including a stationary cylinder and a piston reciprocable therein, a pilot valve actuated selectively by said flyballs to admit pressure fluid to said cylinder or permit the escape of fluid therefrom, a second

cylinder closed at one end and disposed within said piston so as to move therewith, a plunger reciprocable in said second cylinder, a valve controlling the flow of fluid into and out of the chamber between said plunger and the closed end of said second cylinder, a lever swingable about a fixed pivot in opposite directions from a neutral position, means connecting said lever to said plunger, and means resiliently increasing or decreasing the loading of said flyballs according to the direction and extent of lever movement away from said neutral position.

3. A governor having, in combination, rotary flyballs, a main speeder spring loading said flyballs and selectively adjustable to vary the speed setting of the governor, an auxiliary spring acting on said flyballs to supplement the force of said main spring in opposing the centrifugal force exerted on the flyballs, an element connected to said auxiliary spring and movable in opposite directions from a neutral position in which no force is exerted by the spring, said element being movable in opposite directions away from said neutral position to create forces acting in opposite directions on said flyballs, a member variably movable in opposite directions in accordance with speed changes detected by said flyballs, compensating mechanism including a part initially movable with said member to actuate said element and stress said auxiliary spring correspondingly and then to move reversely at a controlled rate whereby to produce temporary speed droop, and a secondary spring means energized selectively in accordance with the direction of movement of said element out of said neutral position and assisting said auxiliary spring in moving the element reversely to said neutral position.

4. An isochronous governor having, in combination, an axially shiftable rod, spring loaded flyballs rotatable around said rod and acting on the rod intermediate the ends thereof to shift the rod in opposite directions with opposite speed changes, a power actuated member, control means associated with one end of said rod and operable to control the application of power to said member to cause movement thereof in accordance with the rod movement, spring means acting on the opposite end of said rod, and compensating mechanism actuated in response to movement of said power actuated member and operable to variably stress said spring means so as to impart a temporary speed droop characteristic to said governor.

5. A governor having, in combination, a rotary head carrying flyballs, a main speeder spring coiled about the axis of said head and acting on said flyballs, a pilot valve on the opposite side of said head including a stem having an end projecting through said head and said coiled spring, an auxiliary speeder spring acting on said projecting end and adapted to be stressed selectively to increase or decrease the loading of said flyballs, an hydraulic actuator energized selectively under the control of said valve and having a movable speed regulating member, and mechanism responsive to the movement of said member and operable to vary the stress of said auxiliary spring and impart temporary speed droop to said governor.

6. An isochronous governor having, in combination, spring loaded rotary flyballs, a lever swingable about a normally fixed fulcrum, spring means connected between said lever and said flyballs and being normally inactive when said lever is disposed in a predetermined neutral posi-

tion, said spring means operating by movement of the lever in opposite directions away from said position to respectively increase and decrease the loading of said flyballs, a second spring means connected between said lever and a fixed point and acting in the same direction as said first mentioned spring means to urge said lever toward said neutral position, and compensating mechanism actuating said lever to impart a temporary speed droop characteristic to the governor.

7. An isochronous governor having, in combination, spring loaded rotary flyballs, a lever swingable about a normally fixed fulcrum, spring means connected between said lever and said flyballs and being normally inactive when said lever is disposed in a predetermined neutral position, said spring means operating by movement of the lever in opposite directions away from said position to respectively increase and decrease the loading of said flyballs, a second spring means connected between said lever and a fixed point and acting in the same direction as said first mentioned spring means to urge said lever toward said neutral position, compensating mechanism actuating said lever to impart a temporary speed droop characteristic to the governor, and means by which the effective ratio of said lever may be varied to adjust the stability of the governor.

8. An isochronous governor having, in combination, spring loaded rotary flyballs, a lever swingable about a normally fixed fulcrum in opposite directions from a predetermined neutral position, spring means connected between said lever and said flyballs and being normally inactive when the lever is in said neutral position, said spring means being energized by movement of the lever in opposite directions away from said neutral position to respectively increase and decrease the loading of said flyballs, and compensating mechanism acting on said lever to energize said spring means and cause the latter to impart a temporary speed droop characteristic to said governor.

9. A governor having, in combination, rotary flyballs, spring means exerting a force acting on said flyballs to oppose the centrifugal force thereon, a servo actuator including a stationary cylinder and a piston reciprocable therein, a pilot valve actuated by said flyballs and operable selectively to admit pressure fluid to said cylinder or permit the escape of fluid therefrom, a second fluid filled cylinder closed at one end and movable with said piston, a plunger reciprocable in said second cylinder, a valve controlling the flow of fluid into and out of the chamber between said plunger and the closed end of said second cylinder, said second cylinder, said plunger and said

valve constituting a dashpot, a member movable in opposite directions from a neutral position, an auxiliary spring connected to said flyballs and actuated by said member to increase or decrease the force opposing the motion of said flyballs according to the direction of movement of the member relative to said neutral position, means connecting said member to said plunger whereby the motion of said piston is transmitted to said spring through the intermediary of said dashpot, and a second spring stressed selectively according to the direction of movement of said member away from said neutral position and applying a force to the latter to urge the member back toward said neutral position.

10. A governor having, in combination, rotary spring loaded flyballs, a servo actuator including a stationary cylinder and a piston reciprocable therein, a pilot valve actuated by said flyballs and operable selectively to admit pressure fluid to said cylinder or permit the escape of fluid therefrom, a member movable in opposite directions from a neutral position, an auxiliary coiled spring aligned with the rotational axis of said flyballs and having opposite ends connected to said member and said flyballs whereby to add to or subtract from the loading on said flyballs according to the direction of movement of the member relative to said neutral position, and means connecting said member to said piston including a dashpot having a leak valve for by-passing fluid to permit dissipation of the energy imparted to said spring and restoration of said member to said neutral position following a change in the position of said piston.

11. A governor having, in combination, rotary flyballs, spring means exerting a force opposing the centrifugal force acting on said flyballs, a servo actuator including a stationary cylinder and a piston reciprocable therein, a pilot valve actuated by said flyballs and operable selectively to admit pressure fluid to said cylinder or permit the escape of fluid therefrom, a member movable in opposite directions from a neutral position, an auxiliary spring connected between said member and said flyballs and actuated by said member to add to or subtract from the force exerted by said spring means on said flyballs according to the direction of movement of the member relative to said neutral position, and means for transmitting the motion of said piston to said spring including a dashpot having a valve adapted to leak and permit dissipation of the energy imparted to said spring and restoration of said member to said neutral position.

GEORGE FORREST DRAKE.
